CLOTHES PIN

Douglas Arthur Davidson, 4 Waimana Road,
Takanini, Auckland, New Zealand

Filed May 7, 1973, Ser. No. 357,706

Term of patent 14 years

Int. Cl. D7—05

U.S. Cl. D7—198

FIG. 1.

FIG. 2.

FIG. 3.

FIG. 1 is an elevational view of the clothes pin, the rear side being similar.

FIG. 2 is a side elevational view of FIG. 1, the other side view being similar.

FIG. 3 is a cross-sectional view, taken on line 3—3 of FIG. 1.

What I claim is:

The ornamental design for a clothes pin, substantially as shown and described.
